STRUCTURAL BUILDING UNIT

Norman Thomas Clements, Pittsburgh, Pa.

Application September 2, 1948, Serial No. 47,451

7 Claims. (Cl. 72—38)

1

My invention relates, generally, to structural building units, and, more particularly, to such units in the form of bricks or the like, and to wall or building construction employing such units.

Heretofore, many attempts have been made to provide a structural building unit in the form of a brick or the like having mechanical interlocking and self-spacing features to some degree. None of these attempts has been entirely successful for the reason that no one has provided a unit which may be readily and economically produced, which is as universally applicable as common brick; which is so constructed that it may be readily and economically used in the building of wall or other structures wherein the units are laid up in mortar or laid up dry and left in that condition or the mortar is introduced after the units have been laid; which is so constructed that the units are self-spacing, self-aligning and self-interlocking under all conditions of use; which is so constructed that the units may be accurately and properly laid up with a minimum of time and effort by skilled or unskilled workmen to provide structures which are rigid, strong and accurate to the desired degree, and which are so constructed as to make units of this general nature so readily and economically usable by saving time as distinguished from saving labor that they will be used in almost all kinds of structures and put masonry built structures on a competitive basis with any other type of structure.

It is to the solution of this problem and to the fulfillment of this need for an entirely new and universally usable building unit in the interests of reducing cost of building construction and providing better construction that my invention is directed.

Accordingly, the object of my invention, generally stated, is to provide a novel building unit in the form of a brick or the like which shall be fully as universal in its use and application as the common brick, but which shall be so shaped and constructed that it may be laid up with far greater speed and with less effort by skilled or unskilled workmen than such common brick to provide a wall or other structure which shall be rigid and strong and wherein the units are accurately spaced, aligned and mechanically interlocked.

A more specific object of my invention is to provide a building unit in the form of a brick or the like which is so shaped that it may be used in building wall or other structures in accordance with any known system or procedure by experi-

2

enced as well as unexperienced workmen and a rigid, durable and well appearing structure obtained.

Another object of my invention is to provide a unit of the character described which is so constituted that it may be readily laid up in wall or other structures with or without the use of a suitable adhesive agent, such as cement mortar, or first laid up dry and the adhesive agent introduced thereafter by manual or mechanical means, and which under all conditions shall be self-spacing, self-interlocking and self-aligning.

A further object of my invention is to provide a unit of the character described wherein the self-spacing, self-interlocking and self-aligning functions are provided by the use of predetermined arrangements of cleats and bars on opposed flat faces or surfaces of the unit.

Another object of my invention is to provide a unit of the character described wherein a notched longitudinal cleat portion is provided on one face and a plurality of transverse notched cleat portions and longitudinal bars on the opposite face for imparting self-spacing, self-interlocking and self-aligning qualities or features to the unit.

A further object of my invention is to provide a wall or other building structure constructed of a plurality of building units of the character described in which all of the various units are properly spaced, aligned and interlocked so as to provide a durable and rigid structure with or without the use of mortar or other adhesive.

These and other objects of my invention will become more apparent from the following detailed description of several embodiments thereof when read in conjunction with the drawing, wherein

Figure 1 is a side view, in elevation, of one embodiment of my invention in the form of a building brick, the brick in this instance being shown upside down in order to conform to the showing of the several units in Fig. 3.

Fig. 2 is an end view, in elevation, of the brick of Fig. 1 also shown in upside down position.

Fig. 3 is a view of three of the units standing on their end faces showing the details of the cleat and bar arrangements used on the bottom surfaces or faces of the units.

Fig. 3a shows a plurality of the units laid in a stretcher course with their top faces facing upward.

Fig. 4 is a side view, in elevation, of another embodiment of my invention,

Fig. 5 is a cross sectional view along line V—V of Fig. 4.

Fig. 6 is a plan view of the bottom face or surface of the unit of Fig. 4.

Figs. 7 and 8 are sectional views of a wall structure formed of the units shown in Figs. 4, 5 and 6.

Fig. 9 is a side view, in elevation, of another embodiment of my invention.

Fig. 10 is a top plan view of the unit of Fig. 9.

Fig. 11 is an end view thereof.

Fig. 12 is a perspective view of the units 9, 10 and 11.

Fig. 13 is a bottom plan view of the unit shown in Fig. 9.

Fig. 14 is a cross sectional view of the wall structure employing the unit of Fig. 9.

Fig. 15 is a view, in elevation, of a portion of a veneer wall showing the arrangement of bricks at the corner, and

Fig. 16 is a similar view of another portion of the veneer wall.

Referring now to Figs. 1, 2, 3, and 3a of the drawing, which show one embodiment of my invention as it relates to a building unit in the form of a brick, there is shown a brick 10 of standard or other suitable dimensions which may be formed in any desired manner and of any suitable material, such as clay, cement, plastic, metal or the like.

The brick 10 comprises a body portion 11 having oppositely disposed flat end faces 12 and 13, front and rear side faces 14 and 15 and top and bottom faces 15 and 16.

In Figs. 1 and 2, the brick is shown in an upside down position and, therefore, it is to be understood that the face 15 is the top face or surface of the brick as it is normally used.

In order to provide self-spacing, self-aligning and self-interlocking features, various arrangements of projecting portions are utilized on some of the faces, and these projecting portions will be referred to hereinafter as cleats and bars.

It will be observed that, in this embodiment of my invention, the body portion is provided on its top face or surface 15 with a single cleat 17 extending longitudinally thereof adjacent one edge. While any suitable size and shape of cleat may be employed, it is preferred to use a triangular shaped cleat, as shown, which has a height corresponding to the desired spacing between bricks, such as one-half inch.

The longitudinal cleat 17 is provided with a plurality of cross notches 18, 19, 20 and 21 which have converging side walls and a depth of one-half that of the cleat. These notches are of the same size, that is, the side walls of the notches are spaced and sloped to correspond to the spacing and sloping of the side walls of the cleat.

It is preferred to position these notches in such manner that they are equally spaced with two notches on each side of the midpoint of the body portion, as shown. It will be apparent that the spacing dimensions depend upon the length of the body portion. As an example, however, if the brick is to be of standard 8" length, the spacing between the centers of the notches is $2\frac{1}{8}$ ". The end notches 18 and 21 are spaced from the end faces of the body portion a distance equal to one-half the spacing between notches plus one-half the desired spacing between the ends of adjacent bricks in a stretcher course. If this spacing is one-half inch, then the total distance to be considered in figuring the spacing between notches is eight and one-half

inches which gives a $2\frac{1}{8}$ " spacing between the centers of the notches.

It is to be understood that this is simply an example and that the brick of my invention may be made in any desired size or proportion.

The bottom face or surface 16 of the brick is provided with a plurality of transversely extending cleats 24, 25, 26 and 27 which are of the same cross-sectional shape and size as the longitudinal cleat 17, and which are spaced to correspond with the spacing of the notches 18 through 21.

As best shown in Fig. 2, the transverse cleats are each provided with a full or closed notch 28 and an open-sided or partial notch 29. The closed notch 28 is similar in size and shape to the notches 18, 19, etc. The open-sided notch 25 is of the same depth as the other notches and its single side wall has the same angular position as corresponding side walls of the other notches.

It will be observed that the transverse cleats 24, 25, etc., extend only partially across the face 16 and terminate short of the edge between the bottom face 16 and the front face 15.

Referring now to Fig. 3, it will be observed that each brick is provided on its bottom face or surface with a plurality of bars 31, 32 and 33 extending in aligned relation between the transverse cleats and spaced from the edge of the bottom face 16. These bars are of the same size and shape as the transverse cleats 24, etc., except that they are only one-half as high. In other words, their height corresponds to the depth of the notches, such as 18, 28 and 29.

In addition to the bars 31, 32 and 33, a single half bar 34 is provided between the ends of the cleats 25 and 26. This half bar is of the same shape and dimension as the full bars, except that it is only one-half their size in a transverse direction.

It is to be understood that the cleats and bars referred to may be integral with the body portion of the brick or they may be formed as separate members of the same or different material and attached thereto in any suitable manner. It is believed, however, that the most practical way of making a building unit of this kind is to mold or extrude it in a suitable manner so that it is all in one piece.

Reference will now be made to Fig. 3a for the purpose of further explaining the novel structural features of this brick and the manner in which a plurality of these bricks may be employed in a wall or other structure.

Fig. 3 shows a number of bricks D, E, F, G and H laid in a stretcher course with their top faces 15 facing upward and their longitudinal cleats 17 lying in two adjacent parallel rows as shown.

Fig. 3 shows three of the header or bonding bricks A, B and C with their bottom faces 16 shown in order to illustrate clearly how they fit upon the upper faces of the stretcher bricks of Fig. 3a.

It will be observed that the stretcher bricks are laid with the joints in each row staggered and with the correct spacing between bricks. The header or bonding bricks when placed upon the stretcher bricks will bridge all of the transverse joints, such as 37, 38 and 39 as well as the longitudinal joint 40.

Referring to the middle one B of the three bonding bricks of Fig. 3, it will be apparent that when brick B is placed upon the stretcher bricks of Fig. 3a in the same position as shown, the two middle transverse cleats 25 and 26 will ex-

tend over and interlock with the cleats 17 of the three stretcher bricks D, E and F. In addition, the full bar 32 and the half-bar 34 between cleats 25 and 26 will be positioned within the square of notches 21, 18, 19 and 20 of the bricks E, D and F.

The header bricks A and C interfit with the stretcher bricks in the same manner with brick A covering the joint 38 and brick C covering the joint 39.

It will be understood that the transverse cleats on the bottom faces of the bricks of the header course engage the upper surfaces of the various bricks of the stretcher course and accurately space these bricks apart. In laying the wall or whatever it may be, it is, of course, understood that the first course of stretcher bricks must be accurately leveled and spaced as in any other brick work. Thereafter, however, the successive courses of stretcher bricks or header bricks due to the nature thereof automatically space, align and interlock themselves in the structure.

While, not shown, it will be readily apparent that when successive layers of stretcher bricks are laid, the open sided slots 29 in the transverse cleats interfit with the notches 18, 19, etc., in the longitudinal cleats 17 and accurately align the side faces of the bricks. Due to the fact that the parallel cleats have the same center line spacing as the notches in the longitudinal cleat 17, the bricks may be laid with $\frac{1}{4}$, $\frac{1}{2}$ or $\frac{3}{4}$ lapping. In other words, regardless of the relative longitudinal positions of adjacent courses of stretcher bricks, the open sided notches 29 will always interfit properly with the slots 18, 19, etc., in the longitudinal cleat or cleats 17.

Referring now to the brick structure per se, it is preferred to use cleats of the character shown and described, that is, sharp edge cleats of triangular shape for the reason that when an adhesive agent is employed in laying the bricks, the sharp edged cleats will readily cut through the adhesive agent and produce accurate spacing. As stated hereinbefore, all of the cleats may be integral or separate. They may be made of different material from that of the body portion. They may be formed separately and attached to the body portion while it is in a soft or curing condition, such as when formed of clay or a similar substance.

The use of cleats of this nature also increases the adhesive area or surface of the brick. This will be apparent from the fact that the sloping sides or faces of the cleats together with the flat surfaces therebetween have a total area of more than the flat area of the body portion. Therefore, when an adhesive agent is used, the actual area with which it comes into contact is greater than if a flat surface brick were used.

It is preferred to use four transverse cleats, as shown, together with four equally spaced notches in the longitudinal cleat for various reasons. The use of four transverse cleats strengthens the brick for the reason that the weight supported thereby is distributed between the four points of contact of the cleats. The use of four cleats also makes it possible to cut or break a brick into quarters or halves and still preserve its inherent characteristics insofar as spacing, aligning and interlocking are concerned.

The use of four notches and four cleats together with the open-sided notches 29 in the transverse cleats makes it possible to readily lay the bricks in a stretcher course in any desired manner of overlapping, that is, $\frac{1}{4}$, $\frac{1}{2}$ or $\frac{3}{4}$ overlapping.

As described in connection with Fig. 3, the full center-bar 32 and the half-bar 34 effectively interlock with the notches in the longitudinal cleat 17 which, as will be understood, prevents the header brick from moving along the parallel rows of longitudinal cleats as would otherwise be the case if there were no interlocking bars. In order to increase this interlocking characteristic and make it possible to also provide equally effective interlocking under all conditions of use, the two end bars 31 and 33 are utilized. They are not effective in the arrangement shown in Fig. 3, except to strengthen the brick. When, however, a header course is laid and it is desired to again lay a stretcher course, these end bars 31 and 32 interfit with the notches 28 in the transverse cleats and function to mechanically lock the bricks of the first stretcher course to those of the header course.

It will be observed that the transverse cleats 24, 25, etc., terminate short of the edge of the flat surface upon which they are positioned or short of the front face 14. They are in alignment with the side of the middle half-bar 34 which makes it possible to employ various types of pointing for any structure laid up of these bricks and also possible to effect overlapping if desired. In other words, when stretcher bricks are laid one upon the other, the open-sided notches 29 in the transverse cleats engage the notches 18, 19, etc., in the longitudinal cleats as stated hereinbefore. When, however, it is desired to effect overlapping, such as when building an overhanging wall or structure, the notches 28 in the transverse cleats engage with the notches 18 and 19 in the longitudinal cleats.

The bars 31, 32, 33 and 34, in addition to functioning as interlocking and positioning members, also function to greatly strengthen the body portion of the brick and increase its carrying capacity. As stated hereinbefore, these bars have a height equal to one-half the height of the cleats. In other words, their height is the same as the depth of the notches in all cleats. It will be apparent that this being the case, the horizontal faces of the bars are always spaced from the upper surface of the lower brick. This provides the necessary passage for inserting the adhesive agent between adjacent brick surfaces. In other words, the square area formed by the two middle transverse cleats and the bars extending therebetween may be completely filled with the adhesive agent whether it is introduced by mechanical means or by means of a hand trowel.

It will be apparent that a wall or other structure laid up of bricks of the character described is a completely finished wall insofar as strength is concerned regardless of whether or not an adhesive agent has been used. The inherent nature of these bricks provide complete self-spacing, self-alignment and self-interlocking. Even though the structure is laid up in a dry state without the use of an adhesive agent all of the various bricks, regardless of the style in which they are laid, will be completely mechanically interlocked in such manner that no brick, except those on the top course, may be removed.

In addition, after the first course is properly laid, all of the successive following courses, regardless of whether or not they are stretcher or header courses, will be automatically aligned and spaced as they are laid. The resulting structure is rigid and accurate and if the bricks have been laid dry, the entire structure may be further bonded together by introducing the adhesive

agent by means of a suitable mechanism. All of the various joints and passages between the adjacent bricks, regardless of the position thereof, are open to such extent that the entire structure may be bonded together in a continuous manner.

Referring to Figs. 4 through 6 of the drawing, there is shown another embodiment of my invention which embodies the same general concept as the embodiment just described, but which is of a somewhat simpler nature. As shown in Fig. 4 the brick 50 has a body portion 51, a longitudinal cleat 52 and a plurality of transverse cleats 53, 54, 55 and 56. In this instance, the cleat 52 is also provided with four notches which are equally spaced and of one-half the depth of the cleat. Also, as shown in Fig. 6, the transverse cleats are also provided with open-sided notches 61 and full notches 62 as in the other construction.

While this construction is somewhat simpler to form or make, it is not so completely interlocking as the construction of Figs. 1 through 3. As described in connection therewith, the bars 31, 32, and 33 thereof which are not used in the present construction function to interlock the bricks of the different courses against any movement whatsoever. While this is a desirable feature, it is not necessary under all conditions, particularly in plain veneer brick work where the present construction would be adequate.

Figs. 7 and 8 show the self-spacing and self-interlocking features of this brick. Fig. 7 shows a longitudinal sectional view of a wall laid up of these bricks which illustrates the manner in which the transverse cleats 53, etc., engage the longitudinal cleat 52 to provide the self-spacing as well as the self-interlocking features. It will be understood that regardless of how the header bricks are laid, the same self-interlocking and self-spacing features will prevail.

Referring to Fig. 8, this view shows a transverse cross section through the same wall showing in detail how the two transverse cleats 54 and 55 hook over the adjacent or parallel longitudinal cleats 52.

It will be understood that this brick is so constructed that it may be laid up in any desired manner, that is, it may be quarter lapped, half lapped or three-quarter lapped, since the notches 57, 58, etc. are equally spaced and the spacing of the transverse cleats 53, 54, etc., correspond with the spacing of the notches.

Referring now to Figs. 10 through 14, there is shown a third embodiment of my invention which is of the simplest form.

In this embodiment, the body portion 71 of the brick 70 is provided with a longitudinal cleat 72 on the upper face 73 adjacent one side edge thereof as in the other two embodiments described. It is also provided with a pair only of transverse cleats 74 and 75 on the bottom surface 76, which are spaced apart one on each side of the middle of the body portion.

The longitudinal cleat 72 is provided with a plurality of notches 77, 78, 79 and 80 which, as in the other constructions, have a depth equal to one-half the height of the cleat. In this instance, however, the notches in the cleat 72 are not equally spaced. The two middle notches 78 and 79 are spaced apart the same as the transverse cleats 74 and 75. The spacing between notches 77 and 78 and 79 and 80 is equal but is longer than the spacing between notches 78 and 79.

The transverse cleats 74 and 75 are provided with open sided notches 81 and 82 at their ends and with closed or full notches 83 and 84 intermediate their ends as in the other two constructions. Either the open sided notches or the full notches may engage the middle notches 78 and 79 of the longitudinal cleat 72.

Referring to Fig. 14, there is shown how a number of bricks of this construction may be used in building a wall. This view clearly illustrates the manner in which the adjacent longitudinal cleats 72 of the lower course X of stretcher bricks are engaged by the transverse cleats 74 and 75 of the bricks of the header course Y. This view also shows how the second course Z of stretcher bricks interfit with the header bricks.

Referring now to Figs. 15 and 16, there is shown the manner in which these bricks are laid in a veneer wall structure. Fig. 15 shows the corner 20 of the veneer wall as viewed from the rear or back thereof. This view shows, in detail, how the transverse cleats 75 and 74 on the brick J of the upper course interlock with the longitudinal cleat 72 of brick K and the end notch 80 in the longitudinal cleat 72 of brick L of the bottom course. It will be noted that the open-sided notch 82 of cleat 74 engages the notch 80 of cleat 72 on brick L.

Thus it will be apparent that bricks K and L are properly spaced and tied together by the cleats 74 and 75, and that the proper face alignment between bricks J and L is provided by the engagement of the open-sided notch 82 with the notch 80.

Fig. 16 shows the interlocking and face alignment features of the stretcher bricks of a veneer wall, as viewed from the rear. In this instance, the transverse cleats 75 and 74 of brick M engage the adjacent end notches 77 and 80 in cleats 72 of bricks N and O, which properly spaces the bricks N and O in endwise relation and interlocks them together. In this instance, the open-sided notches 82 and 81 in cleats 75 and 74 are in engagement with the notches 77 and 80 in the longitudinal cleats 72 of bricks N and O and provide the necessary face alignment of the bricks.

The unused notches, such as notches 78 and 79 in the longitudinal cleats 72, may be used as metallic bond inserts.

It will be apparent that, by means of this arrangement and spacing of the notches in the longitudinal cleat 72 and the similar spacing of the transverse cleats 74 and 75, these bricks may be laid in one of two ways. They may be laid one upon the other with their end faces in alignment, in which event the cleats 74 and 75 engage the two middle notches 78 and 79. They also may be laid in one-half overlapping relation, as shown in Figs. 15 and 16, in which event the cleat 74 will engage a notch 80 and cleat 75 will engage a notch 77 of the next brick in the stretcher course.

In view of the fact that the transverse cleats 74 and 75 each have two notches, it will be apparent that these bricks may be laid with their front faces in alignment or offset as desired. When the front faces are in alignment, as shown in Fig. 16, the open-sided notches 81 and 82 engage the slots 77 and 80 in the longitudinal cleats 72. When laid in overlapping relation, the middle notches 83 and 84 in the transverse cleats engage the same notches in the longitudinal cleats.

This construction is particularly desirable where the brick is to be used primarily for veneer

work. It will be apparent, however, that if so desired, the notches in the longitudinal cleat may be equally spaced, as in the other two constructions.

This is the simplest form of the three embodiments of bricks disclosed and is believed to be desirable from the standpoint of cost of manufacture as well as possible loss resulting from damage in handling is concerned. This might be termed a common brick as compared to the other two forms for the reason that it is of simpler form or construction and is as susceptible of general use as ordinary or common brick. While it does not provide complete mechanical interlocking in all ways in which it may be laid, the interlocking that is provided is sufficient for all kinds of brick veneer work. In addition, it has the self-aligning and self-spacing features as well as the inner bonding of the other two constructions.

In view of the foregoing description of detailed examples of the several embodiments of my invention relating to building units in the form of bricks, it will be apparent that these building units are of such nature as to make it possible to widely increase the use of masonry structures for general building purposes and thereby conserve materials of a more scarce and expensive nature.

The building units of my invention are so constituted that they may be readily used by inexperienced as well as experienced workmen and employed in the same manner as common brick to produce similar structures. My building units are so constituted that they provide a better and more substantial and a more accurately constructed wall or other structure in which they may be employed. Their self-spacing, self-interlocking and self-aligning features all contribute to the ease of laying either with or without an adhesive agent and also contribute to the production of a more substantial and uniform structure.

While I have shown and described specific embodiments of my invention, it will be apparent to those skilled in the art that various changes and modifications may be made in any one of these several embodiments without departing from the principles of my invention.

I claim as my invention:

1. A parallelepipedal building unit having at least a pair of opposed flat surfaces, a longitudinally extending cleat of triangular cross section on one flat surface disposed adjacent one edge thereof and having a plurality of equally spaced notches therein of lesser depth than the depth of the cleat, and a plurality of transversely extending cleats on the opposite flat surface being of substantially the same cross section as the longitudinal cleat and spaced apart in accordance with the spacing of the notches therein, said transversely extending cleats having open sided notches at the corresponding ends thereof at one edge of said opposite flat surface corresponding in depth to the height of the longitudinal cleat less the depth of the notches therein.

2. A building unit in the form of a brick comprising, a body member having at least a pair of opposed flat faces, a longitudinally extending cleat portion on one face adjacent an edge thereof, said cleat portion having four spaced notches therein, a pair of transversely extending cleat portions on the opposite flat face, said cleat portions being spaced apart a distance equal to the spacing between the middle two of the notches in the longitudinal cleat portion and having open sided notches at corresponding ends correspond-

ing in depth to the height of the longitudinal cleat portion less the depth of the notches therein.

3. A building unit in the form of a brick comprising, a body member having at least a pair of opposed flat faces, a longitudinally extending cleat portion on one face adjacent the edge thereof, said cleat portion having four notches therein of a depth equal to one half the height of the cleat portion, said notches being so spaced that the distance therebetween is equal and the end notches are positioned from the end faces of the body member a distance of not more than one half the distance between any two of the said four notches in the cleat portion, four transversely extending cleat portions on the opposite face spaced apart to correspond to the spacing of said notches in the longitudinal cleat portion, said transverse cleat portions having open sided notches at corresponding ends equal in depth to said other notches and full notches intermediate their ends of similar depth, and a pair of longitudinally extending bar portions positioned in parallel relation between the two middle transverse cleat portions.

4. As a new article of manufacture, building unit in the form of a brick having at least a pair of opposed flat faces, a longitudinally extending triangular-shaped cleat portion on one face adjacent one side edge thereof, said cleat portion being of such height as to provide proper spacing between such units when laid up one upon the other and having four spaced notches therein one half the depth of the cleat portion, said notches being equally spaced with the two end notches spaced from the end faces of the unit a distance less than one half the spacing between notches, four transversely extending triangular-shaped cleat portions on the opposite flat face of the unit spaced apart longitudinally of the unit in the same positions as the notches in the longitudinal cleat portion and being of the same height as said longitudinal cleat portion, said transverse cleat portions extending from the side edge of this face adjacent the side edge along which the longitudinal cleat portion is positioned and terminating short of the opposite side edge of the face on which they are positioned, said transverse cleat portions each having a notch therein intermediate their ends and in longitudinal alignment, said notches in the transverse cleat portions being of the same depth and shape as the notches in the longitudinal cleat portion and being spaced from the ends of their respective transverse cleat portions which terminate at the side edge of the face a distance equal to the distance between the end notches in the longitudinal cleat portion and the end faces of the unit, a bar portion extending between each transverse cleat portion, said bar portions being positioned to one side of the notches in the transverse cleat portions and being of the same height as the bottoms of the notches, and an additional bar portion extending between the ends of the two middle transverse cleat portions which terminate short of the side edge, said additional bar portion having the same cross sectional shape as one longitudinal half of the other bar portions and being of the same height.

5. A building brick comprising, a body member having at least a pair of opposed flat surfaces, a single longitudinally extending cleat portion on one side only of the flat surfaces adjacent one edge thereof, said cleat portion having a plurality of spaced transverse notches therein. said

notches being of a depth less than the height of the cleat portion, and a plurality of transversely extending cleat portions on the opposed flat surface, said transversely extending cleat portions being equal in number to and having substantially the same spacing as the transverse notches in the longitudinally extending cleat portion and having their corresponding ends provided with open-sided notches having a depth equal to the height of the longitudinally extending cleat portion less the depth of the notches therein.

6. A building brick comprising, a body member having at least a pair of opposed flat surfaces, a longitudinally extending cleat portion on one side only of the flat surfaces adjacent one edge thereof, said cleat portion having four spaced transverse notches therein, said notches being equally spaced with the end notches equally spaced from the ends of the cleat portion a lesser distance than the spacing between notches and a plurality of transversely extending cleat portions on the opposed flat surface, said cleat portions being equal in number to and having substantially the same spacing as the notches in the longitudinally extending cleat portion and having open-sided notches at corresponding ends thereof having a depth equal to the height of the longitudinal extending cleat portion less the depth of the notches therein.

7. A building unit comprising, a body member having at least a pair of opposed faces, a triangular-shaped cleat portion on one face thereof extending longitudinally thereof along one edge, said cleat portion having four equally spaced transverse notches therein, four spaced triangular-shaped cleat portions of substantially the same height as the longitudinal cleat portion on the opposite face extending transversely thereof from one longitudinal edge and terminating short

of the opposite edge and having the same spacing as the notches in the longitudinal cleat portion, said transverse cleat portions each having notches therein intermediate their ends and in longitudinal alignment and open-sided notches at corresponding ends terminating at said one longitudinal edge, said notches and open-sided notches having a depth equal to the height of the longitudinal cleat portion less the depth of the notches therein, a plurality of bar portions extending in longitudinally aligned relation between said transverse cleat portions intermediate the notches in said transverse cleat portions, and an additional single bar portion extending between the middle two of the transverse cleat portions and spaced in parallel relation with the other bar portion extending therebetween a distance substantially equal to the spacing of the notches in the longitudinal cleat portion.

NORMAN THOMAS CLEMENTS.
